UNITED STATES PATENT OFFICE.

NATHANIEL K. SHELTON, OF WABASH, INDIANA.

IMPROVEMENT IN CARPET-STRETCHERS.

Specification forming part of Letters Patent No. 136,339, dated February 25, 1873.

To all whom it may concern:

Be it known that I, NATHANIEL K. SHELTON, of Wabash, in the county of Wabash and State of Indiana, have invented a new and valuable Improvement in Carpet-Stretchers; and I do hereby declare that the following is a full, clear, and exact description of the construction and operation of the same, reference being had to the annexed drawing making a part of this specification, and to the letters and figures of reference marked thereon.

Figure 1 of the drawing is a representation of longitudinal central section. Fig. 2 is a plan view of the same.

This invention has relation to wooden carpet-stretchers; and it consists in the construction and novel arrangement of a pair of wooden beam-levers perforated to receive a fulcrum-pin, and having at their outer ends toothed wooden heads provided with diagonal braces, which are mortised on each side of said heads and beam-levers, thereby producing a strong and firm wooden carpet-stretcher, as herein-after more fully described.

Referring to the accompanying drawing, Δ Δ' designate a wooden pair of beam-levers, crossing each other and connected together by means of a fulcrum-pin, b . The lever Δ is slotted or bifurcated longitudinally to receive the lever Δ . Both levers are correspondingly perforated, as shown at a , so that the fulcrum-pin may be adjusted to adapt the stretcher to rooms of different widths. Each lever is pro-

vided with a head, B' , which is armed with pins or teeth e , to be inserted in the carpet near the edge thereof. These heads B' are each provided with mortised diagonal braces h near the outer ends thereof, extending up a short distance, and mortised to the beam-levers, as shown. The bifurcated lever Δ is represented with a neck, z , and bevel shoulders z^2 , to which the braces h are mortised, whereby a very strong beam-lever is made, and well adapted to this purpose. After said teeth are inserted in the carpet, the levers are pressed down to a horizontal position to stretch the carpet, and are held in such position by means of a band, e' , which passes around the lever Δ , and is arranged to slide over the end of the lever Δ' .

What I claim as my invention, and desire to secure by Letters Patent, is—

The wooden carpet-stretcher described, consisting of the bifurcated beam-lever Δ and the beam Δ' , both perforated for the fulcrum-pin b , and having at their ends the toothed heads B' , provided with diagonal braces h , mortised into said heads and said beams on each side thereof, constructed and arranged as set forth.

In testimony that I claim the above I have hereunto subscribed my name in the presence of two witnesses.

NATHANIEL K. SHELTON.
